UNITED STATES PATENT OFFICE.

FRANK L. JOYCE, OF DAYTON, OHIO.

DESIGN FOR A LIFTING-JACK STAND.

SPECIFICATION forming part of Design No. 25,361, dated April 7, 1896.

Application filed August 1, 1895. Serial No. 557,909. Term of patent 14 years.

To all whom it may concern:

Be it known that I, FRANK L. JOYCE, a citizen of the United States, residing at Dayton, in the county of Montgomery and State of Ohio, have invented and produced a new and useful Design in Lifting-Jack Stands, of which the following is a specification.

Figure 1 is a perspective view of a lifting-jack, showing my design. Fig. 2 is a perspective view of the same, taken from the opposite side. Fig. 3 is a cross-section of the standard and overhanging circular body, these three views being deemed necessary to fully illustrate my design.

15 The leading feature of my design consists of a central column substantially rectangular at the top and bell-shaped at the bottom, where it joins a right-angled flaring base, there being joined to the central column near 20 the top a circular body which overhangs the central column.

a represents the central column, and a' the base or flange on which the central column rests. The upper portion of the column is 25 substantially rectangular, as shown at a^2 , and the lower portion bell-shaped, as shown at a^3 , the rectangular portion and the bell-shaped portion being connected by ribs a^4 , which are also extended down so as to join the flange or

base a' . At the rear the rectangular portion 30 of the central column is provided with a semi-circular boss a^5 , and opposite this boss is an enlarged circular body b , which is joined to the central column at one side, so as to overhang the same. Extending forwardly from 35 the overhanging circular body b are plates or flanges b' , having therein ribbed or flanged openings b^2 , as shown in Fig. 1. The rib or ribs a^6 , which are on the side of the central column on which the overhanging circular 40 body b is joined, is extended out so as to join the said circular body, the ribs being curved outwardly to conform to the bell-shaped portion of the lower column and joined onto the flange, thus presenting to the eye a regular 45 outline for the ribs, with an irregular outline for the body or column.

Having thus described my invention, what I claim is—

The new and original design for lifting-jack stands substantially as hereinbefore described and specified.

In testimony whereof I have hereunto set my hand this 24th day of July, A. D. 1895.

FRANK L. JOYCE.
